TIEPLATE

Frederick L. MacQuarrie, Pittsburg, Calif.

Application November 2, 1932, Serial No. 640,904

3 Claims. (Cl. 238—298)

This invention relates to improvements in tie plates. More specifically, the invention relates to the form of construction of the tie bearing portion of a tie plate. The tie bearing surface of my improved plate is such that it efficiently offers resistance to both longitudinal and lateral creeping, and is self-seating in the event that the spikes become loose. Substantially the entire undersurface of my improved plate comprises shallow pyramidal depressions whose oblong bases are longest in the direction of the length of the rail. Such a structure provides a tie bearing surface which will not cut the fiber of the ties, yet it enables the plate to adequately resist both longitudinal and transverse thrusts, the configuration of each depression being such that there is a greater resistance offered in the direction transverse to the length of the rail than in a direction longitudinally thereof.

For a more complete disclosure of the invention reference may be made to the following detailed description and accompanying drawing.

In the drawing—

Fig. 1 is a side elevation of a tie plate embodying my invention;

Fig. 2 is a view of the underside of the tie plate;

Fig. 3 is a vertical section on line 3—3 of Fig. 1;

Fig. 4 is an end view of a tie plate similar to the above, but having in addition a pair of tie penetrating ribs on the underside thereof which extend in the direction of the length of the rail.

Referring in detail to the drawing, 10 represents the tie plate as a whole, which in the embodiment illustrated has a canted rail engaging upper surface 12 and a rail flange abutment 14 extending in the direction of the length of the rail.

The underside or tie bearing surface of the plate is formed of a plurality of rows 16 of substantially pyramidal depressions 18. The depressions 18 are formed by the intersection of a plurality of girder portions 20 of substantially triangular shape in cross section and beam portions 22 of similar shape in cross section. The base width g of the girder portions 20 is less than the base width b of the beam portions. Similarly, the altitude g' of the girder portions 20 is slightly greater than the altitude b' of the beam portions. Thus the flat or blunt apexes g^2 of the girder portions lie in a plane lower than the flattened blunt apexes b^2 of the beam portions.

With such a disposition and proportioning of the beam and girder portions, it is apparent that the beam portions span or bridge the spaces between the girder portions. Due to the fact that the base width g of the girder portions is less than the base

width b of the beam portions, the inclined faces of beam portions are at a steeper angle to the horizontal than the beam portions. This relative steepness of each girder portion endows the same with greater resistance to thrust in the direction transverse to the rail than that offered by each beam portion in the direction of the length of the rail. This relative proportioning of the respective base widths of the beam and girder portions results in the formation of the substantially pyramidal depressions referred to. These depressions have oblong shaped bases, whose greatest dimension extends in the direction of the length of the rail, or, in other words, in the direction of the rail abutment rib 14. The oppositely inclined walls of the pyramidal depressions terminate at their upper extremities in small rectangular areas a . These areas are not intended to form any substantial bearing on the tie. The load on the tie plate is carried in almost its entirety by the multiplicity of oppositely inclined walls of the intersecting beam and girder portions, which form the pyramidal depressions. Thus, in use, the body of the tie conforms itself to the shape of the pyramidal depressions. These are relatively so shallow that there is little or no cutting of the fibers of the tie.

Each pyramidal depression exerts sort of a compressing action on that portion of the tie on which the plate is seated. This arrangement provides a tie plate, which is light in weight and one which can be manufactured quickly and cheaply and yet give extremely good service in practice. The improved tie plate may be provided with suitable spike holes 24, such as indicated in Fig. 2. These may be located to suit the requirements for the particular size of base flange of the rail supported by the tie. At each end of the tie plate, beyond the area formed by the pyramidal depressions, there are upwardly and outwardly inclined marginal bearing portions 23, which extend parallel to and in the direction of the girder portions. These flat margins make a neat finish for the plate and also present a non-undulating undersurface at the extreme ends thereof. This provides a plane surface which may seat firmly on the tie in such a way as to prevent the inward seepage of moisture, it being understood that when the tie plate has been in use for a short length of time it becomes embedded in the tie to an extent approximating the altitude g' of the girder-like supporting portions.

Instead of having substantially the entire undersurface formed of girder portions, all of which are of uniform altitude, as in Figs. 1 to 3, in some

cases, as illustrated in Fig. 4, I may form two of the girder portions in such a way that they have a greater altitude so as to provide tie penetrating ribs thereon, such as indicated at 26. Otherwise the construction of Fig. 4 is substantially the same as illustrated in the other figures and further description is unnecessary.

A tie plate embodying the intersecting triangular beam and girder portions has the advantage of extreme lightness coupled with adequate strength to resist the stresses to which plates of this character are subjected. The cross grillage or checker work formed by the beam and girder portions provides for such a disposition of the metal constituting the plate that high compressive strength is secured per unit of weight. Thus, a large tonnage of extremely efficient plates can be produced quite economically. This is an important manufacturing advantage, which will be apparent to those skilled in the art.

Modifications may be made by those skilled in the art without departure from the invention, hence the claims are to be interpreted as broadly as is consistent with the teachings of the prior art.

What I claim is:—

1. A tie plate having a tie engaging undersurface comprising a plurality of intersecting blunt ended beam and girder portions of obtuse triangular cross section, the adjacent beam portions being spaced apart a distance substantially equal to their base widths and the girder portions being similarly spaced apart a distance substantially equal to their base widths, the inclined walls of said beam and girder portions forming substan-

tially the entire tie engaging area of the undersurface of the plate.

2. A tie plate comprising an upper rail supporting surface and having a tie bearing undersurface consisting of a plurality of intersecting blunt ended beam and girder portions substantially triangular in cross section and disposed at right angles to one another, the adjacent beam portions being spaced apart a distance substantially equal to their base widths and the girder portions being similarly spaced apart a distance substantially equal to their base widths and flat marginal upwardly and outwardly inclined bearing portions which provide plane surfaces adapted to seat on the tie so as to prevent the inward seepage of moisture, the inner ends of said marginal bearing portions lying in substantially the same plane as the lower extremities of said girder portions and the lower extremities of the girder portions lying in a plane below said beam portions. 15

3. A tie plate having the greater portion of its tie bearing undersurface formed of the intersecting side walls of a plurality of beam and girder portions of obtuse triangular cross sectional contour having blunt apexes, the spacing between 25 the adjacent beam and girder portions being substantially equal to the base widths thereof substantially as described, said tie plate having outer marginal flat bearing portions disposed in the plane substantially coincident with that of the 30 blunt ends of the girder portions, the lower extremities of said beam portions being located in a plane above the lower extremities of said girder portions.
